[57] CLAIM

The ornamental design for a steerable catheter handle,
as shown and described.

DESCRIPTION

FIG. 1 is a top, front, right side perspective view of a
steerable catheter handle showing my new design, the
broken line showing of the catheter is for illustrative
purposes only and forms no part of the claimed design;
FIG. 2 is a top plan view of the design;
FIG. 3 is a bottom plan view of the design;
FIG. 4 is a front view of the design;
FIG. 5 is a right side view of the design, the left side
being a mirror image; and,
FIG. 6 is a rear view of the design.

*FIG. 1**FIG. 2**FIG. 3*FIG. 4

FIG. 5
